UNITED STATES PATENT OFFICE

WILLIAM R. WESTFALL, OF KEW GARDENS, NEW YORK, ASSIGNOR TO SCOVILL MANUFACTURING COMPANY, OF WATERBURY, CONNECTICUT, A CORPORATION OF CONNECTICUT

DESIGN FOR AN ASH RECEIVER OR SIMILAR ARTICLE

Application filed April 1, 1931. Serial No. 39,320. Term of patent 3½ years.

To all whom it may concern:

Be it known that I, WILLIAM R. WESTFALL, a citizen of the United States, residing at Kew Gardens, Long Island, in the county of Queens and State of New York, have invented a new, original, and ornamental Design for an Ash Receiver or Similar Article, of which the following is a specification, reference being had to the accompanying drawings, forming part hereof.

Figure 1 is a top plan view and

Figure 2 a side elevation of an article made according to my design.

The design consists of a main body portion of cylindrical contour, a rounded bottom portion below the main portion and formed by sloping the sides of the article sharply in-

wardly and then sharply downwardly, thus making a well-defined bulge at the lower extremity, and a top portion, of contrasting color to the main and bottom portions, and formed by sloping the sides sharply inwardly, and then sharply outwardly at a corresponding angle to the horizontal, the apex of the angle formed by the thus sloping sides giving to the article a greatly constricted neck portion.

The flaring vacuum cup attached to the main body portion adds to the pleasing appearance of this design.

I claim as my invention:

The ornamental design for an ash receiver or similar article, as described and shown.

WILLIAM R. WESTFALL.
